MAGAZINE PENCIL

Filed Nov. 30, 1929

Inventor
Jacob Rosenthal

By his Atty's Darby & Darby

UNITED STATES PATENT OFFICE

JACK ROSENTHAL, OF BROOKLYN, NEW YORK

MAGAZINE PENCIL

Application filed November 30, 1933. Serial No. 410,883.

This invention relates to a magazine pencil and more particularly to improvements in a continuous feed magazine pencil of the push feed type.

5 The object of my invention includes the provision of an efficient push feed magazine pencil whereby leads are fed continuously from a magazine by a special mechanism described below.

10 Another object of the invention is the provision of a push feed pencil having but few parts and wherein all of the parts are rugged and not liable to break or get out of order.

15 My invention further provides a lead feeding and lead holding mechanism which includes a double cone chuck member acting in combination with means which engages one of the conical surfaces for closing the elements of the chuck member upon the lead to thus hold said lead in writing position, and means in the form of a suitably retarded floating sleeve for acting on the other conical surface to thereby close the chuck elements upon the lead and grip it during the time the said lead is being advanced to a new writing position. The chuck member is also provided with spaced flanges which, under certain conditions, serve as stops for the floating sleeve.

20 Other objects will appear hereinafter and I obtain these objects by a construction illustrated in the accompanying drawing in which—

25 Figure 1 is a longitudinal sectional view showing the mechanism in normal position, that is the mechanism is holding the lead in writing position;

30 Fig. 2 is a longitudinal section view showing the mechanism in fully advanced position and ready to be returned to normal position;

35 Fig. 3 is a transverse sectional view on the line 3—3 of Fig. 2;

40 Fig. 4 is a section on the line 4—4 of Fig. 1;

45 Fig. 5 is a view of my new double cone chuck member; and

50 Fig. 6 is a front end view of the frictionally retarded sleeve member.

Like numerals refer to similar parts throughout the several views.

55 It is one of the prime purposes of my in-

vention to provide a self feeding pencil of the push type which is simple in construction, efficient in operation, and whereby leads are firmly held in writing position by a simple double cone chuck member which also operates in combination with a frictionally retarded floating sleeve or member for closing the chuck elements upon the lead when the same is moved in advanced position, thereby having but few moving parts and these parts are all of substantial and rugged construction. Said parts cooperate with the relatively fixed parts which are firmly held in the outer pencil barrel as will be explained more fully below.

60 In a preferred form of construction the pencil comprises an inner barrel 10 and an outer barrel 11 slidably united. The inner barrel 10 is provided at its lower or tip end with a chuck carrying cup 12. This cup has a sloping bottom for guiding the leads into an opening 13 into which is fitted the threaded end 14 of the chuck member 15. A frictionally retarded floating sleeve or member 16 having a partition wall 18 with an opening therein and a continuous cup member 17 is held upon the chuck member so as to move within the limits of flanges 23 and 24 when the chuck member is reciprocated. The lower end of the frictionally retarded floating sleeve or member is provided preferably with four slits 20 whereby the friction skirts 19 are formed for engaging member 37 to thereby retard the movement of sleeve 16. The chuck member 15 is provided with three slits 26 thereby providing the resilient members or elements in the form of cone members 21 and 22 having their conical bases separated by flange 23, mentioned above. The cone surfaces 21 are adapted to engage the limiting stop 40 of the tip sleeve 39. By thus engaging the stop 40 the split chuck members or elements 29 are clamped upon the lead by the enlarged clamping surface 27, as is shown in Fig. 1. A spring 41 firmly holds the parts distended so that the lead 28 is held in writing position. The upper part of the inner barrel is provided with a threaded sleeve 31 which carries an eraser 32. On the outer side

65 of the threaded sleeve 31 there is frictionally 70

engaged a push cap 30 for operating the pencil.

The outer barrel 11 is provided with a conical extension 33 into which is fitted a tip or holding member 34. This holding member is provided with a inner threaded surface 42 which engages a similar surface of the lead guide member 35. This guide member has a lead holding part or member 36 for frictionally engaging the lead and preventing it from falling through. In order to provide resiliency for the lead holding member 36 the tip member is cut into two sections by a slit 44, shown in dotted lines. A second 15 threaded surface 38 on the lead guide member engages a similar threaded surface on the tip sleeve 39. This tip sleeve is in the form of a cup having a cone engaging stop or opening 40 for the purposes mentioned above. It should be noted that flange 23 acts as a 20 stop for member 18 only when the chuck has no lead, for when lead is in the chuck part 18 engages 22. From the description just given it will be noted that the lead guide 25 member and the tip sleeve are held securely in the tip 33 of the outer barrel by means of the holding member 34 being firmly screwed onto this threaded portion 42, as shown.

From the description thus far given it is 30 apparent that the inner barrel is reciprocated with respect to the outer barrel whenever the cap is pushed downward and the outer barrel is held, as may be done by holding it in the hand and pushing on the cap 35 with the thumb. When so operating the pencil, the chuck carrying cup, which is held on the lower or tip end of the inner barrel, is moved towards the tip of the pencil from the position shown in Fig. 1 to the position shown 40 in Fig. 2.

In thus moving the parts of the pencil the upper conical surface 21 disengages from the stop 40 and when thus disengaged the resiliency of the chuck arms will open the chuck 45 elements so as to momentarily disengage the clamp surface 27 from the lead. The moment that the lower or tip cone surface 22 strikes the chuck engaging part or partition wall 18 of the frictionally retarded floating 50 sleeve or member 16, the clamp surface 27 again closes on the lead and as the parts are moved forward the lead is moved forward also to the limit of the stroke (see Fig. 2). The friction parts or skirts 19 engage the 55 outer surface of the cup-like member 37 with sufficient intensity to cause the floating member to lag until parts 24 and 18 engage, when the chuck member is returned to its normal position, thereby permitting the clamp 60 surface to open and release the lead as the chuck member recedes. The operation described is repeated and with each repetition the lead is fed forward a definite distance and is temporarily held first by the lead 65 holding parts 36 and in final writing posi-

tion by the combination of said parts and the chuck members or elements 29, as explained above. It is noted that my construction permits the use of short lengths of lead to be fed, as by holding the pencil vertically 70 leads will be fed by gravity before entering part 36.

Having now described my invention, what I claim as new and useful and desire to secure by Letters Patent is:

1. In a push feed pencil, an outer barrel and an inner barrel slidably held in said outer barrel, a cup mounted on said inner barrel to form therewith a magazine for leads, said cup having an aperture in its bottom, a chuck member secured in said aperture, said chuck member having lead engaging surfaces and two conical outer surfaces, means carried by the outer barrel for engaging one of said conical outer surfaces for closing the lead engaging surfaces upon the lead, a sleeve on said chuck member, said sleeve having means thereon for engaging the other of said outer conical surfaces of the chuck member to close the lead engaging surfaces upon the lead when the chuck is moved forward for carrying the lead forward to a new position, and means on the outer barrel for engaging said sleeve to frictionally retard its motion.

2. In a push feed pencil, an outer barrel and an inner barrel slidably held in said outer barrel, a cup mounted on said inner barrel to form therewith a magazine for leads, said cup having an aperture in its bottom, a chuck member secured in said aperture, said chuck member having inner lead engaging surfaces and upper and lower conical surfaces, a stop for said upper surface for closing the lead engaging surfaces upon the lead and holding the same in writing position, a sleeve on said chuck member, said sleeve having means thereon for engaging the lower of said surfaces of the chuck member to close the lead engaging surfaces upon the lead when the chuck is moved forward and thereby carry said lead forward to a new position, and means carried by the outer barrel for guiding and frictionally retarding said sleeve.

3. In a push feed magazine pencil, the combination of an outer and an inner barrel slidably united, a cup member having an aperture in its bottom, said cup member mounted on said inner barrel to form therewith a magazine for leads, a chuck member secured in said aperture, said chuck member having depending jaws including tapered portions arranged base to base with a flange therebetween and having inner lead engaging surfaces, a limiting stop flange for engaging an outer surface of said chuck member, a member floatingly carried on said chuck member for engaging another of said outer surfaces when said chuck member is moved in a forward direction, a flange on said chuck member for limiting the movement of said float-

- ingly carrying member, and means for frictionally retarding the movement of said floatingly carried member.
4. In a push feed magazine pencil, the combination of an outer barrel and an inner barrel slidably united, a cup member having an aperture in its bottom, said cup member mounted on said inner barrel to form therewith a magazine for leads, a chuck member secured in said aperture, said chuck member having inner lead engaging means and outer conical surfaces, stop means fixed with respect to the outer barrel for closing the lead engaging means of said chuck member on the lead, a member floatingly carried on the chuck member, said floatingly carried member having chuck closing means and friction skirts, and means carried by said outer barrel for engaging said skirts.
- 20 5. In a lead feeding mechanism for magazine pencils, a chuck member comprising flexible chuck elements and having inner lead engaging surfaces and outer conical surfaces, flanges on said chuck member between which one of said conical surfaces is located, a sleeve floatingly maintained between said flanges for engaging one of said surfaces when the chuck member is moved in lead feeding direction, and means for engaging the other of said surfaces for closing the chuck member upon a lead to be held in writing position.
- 25 6. In a lead feeding mechanism for magazine pencils, a chuck member having chuck elements with tapered jaws disposed to form two conical surfaces in combination with means for engaging one of said surfaces for closing the chuck elements, a frictionally retarded floating member positioned to act on the other of said conical surfaces, means for retarding said floating member, and means for reciprocating said chuck member.
- 30 7. A lead feeding and lead holding member comprising a threaded hollow stem and flexible arms formed into a conically surfaced chuck member having inner lead engaging surfaces to grip a lead, spaced flanges on said chuck member a sleeve having a partition wall floatingly disposed between the said spaced flanges, and relatively fixed means for engaging one of said conical chuck surfaces for holding the lead in writing position.
- 35 8. A lead feeding and lead holding chuck member for push feed pencils having a hollow stem and chuck elements, said chuck elements having inner lead engaging surfaces for gripping the lead to hold the same in writing position, a sleeve, a stop member, and outer upper and lower conical surfaces, the upper conical surface engaging with a stop member to close the lead holding surfaces upon a lead for feeding the lead forward and the lower conical surface arranged to engage a floating sleeve, and means for retarding said floating sleeve.
- 40 9. In a push feed magazine pencil, the combination of an outer and an inner barrel slidably united, a cup member having an aperture in its bottom, said cup member mounted on said inner barrel to form therewith a magazine for leads, a chuck member secured in said aperture, said chuck member having inner lead engaging surfaces and outer conical surfaces separated by a flange, a member floatingly carried on said chuck member for engaging one of the outer surfaces when said chuck member is moved in forward direction, and means for retarding the movement of said floatingly carried member.
- 45 In testimony whereof I have hereunto set my hand on this 27th day of November, A. D. 1929.
